UNITED STATES PATENT OFFICE

CHARLES JEAN-BAPTISTE VIGUERIE, OF PARIS, FRANCE.

GRAIN SEPARATOR.

Application filed June 9, 1925, Serial No. 36,015, and in France June 14, 1924.

The present invention relates to grain separators particularly utilizable for sorting one or several kinds of grains or seeds out of a mass of commingled grains or seeds, 5 of the type described and illustrated in the co-pending application Ser. No. 19,104 and it has for its object to still further improve this type of grain separator particularly with a view to materially enhancing its sorting capacity for a limited volume of the apparatus.

Briefly stated, the present improvements consist in arranging the frusto-conical ring members of which the annular separating 15 elements are made up externally of their supporting cylinder with their inner edges fixed adjacent to said cylinder in juxtaposed relation and their outer free edges remote from said cylinder slightly spaced apart as 20 to provide narrow passages extending circumferentially. They further consist in providing both the outer and inner faces of each of such ring members with a large number of contiguous alveoli or sockets so 25 sized, shaped and arranged as to pick up the proper grains or seeds from their commingled mass. They still further consist in providing pivoted scoops between the pairs of cooperating socketed ring members 30 for receiving whatever grains or seeds are picked up by their inner alveoli or sockets and for suitably discharging them.

With such features and such others as will 35 incidentally appear in the following description, the present invention comprises the novel construction, combination and arrangement of parts that will now be described with reference to the accompanying drawing wherein:—

Fig. 1 is a longitudinal sectional view of 40 the improved grain separator according to the invention.

Fig. 2 is a transverse sectional view of same taken on the line N—O, Fig. 1.

Fig. 3 is an enlarged fragmentary sectional view of same showing four adjacent ring members as represented in Figs. 1 and 2.

Fig. 4 is a partial sectional view of same, taken on the line P—Q, Fig. 2.

Fig. 5 is a side elevational view of a constructional detail.

Fig. 6 is a sectional view of such detail taken on the line R—S, Fig. 5.

Like reference characters designate like 55 parts throughout the several views.

The improved grain separator shown in

these figures comprises a substantially horizontal shaft 1 rotatively mounted in bearings 2 and 3 within a stationary prismatical or cylindrical drum-like casing 4, which shaft 60 carries an outer driving pulley 5 and an internal cylinder 6. Upon the outer surface of this cylinder are fixedly secured in any approved way a plurality of annular separating elements constituted by frusto-conical, i. e. dish-shaped ring members 7 arranged pairwise in juxtaposed relation to one another as shown for forming, as it were, a zig-zag or saw-tooth outline so as to form between them grooves or flutings 7a 70 having the shape of isosceles triangles, the apices of which are situated on the wall of the cylinder 6. Each ring member 7 may be in one piece or formed of a plurality of segments such as 8 (Fig. 2), such segments 75 being advantageously spaced slightly as at 9.

The ring members 7 are secured to the outer face of the cylinder 6 in any suitable way and preferably so as to be readily dismountable. They are formed along 80 their inner edge, i. e. the one which is positioned adjacent the cylinder 6 with slits 10 for a purpose to be hereinafter set forth. Their outer free edges, i. e. those edges remote from the cylinder 6 are slightly spaced 85 apart so as to form narrow passages 32 extending circumferentially, also for a purpose to be hereinafter described. The outer and inner faces of each ring member 7 are formed with a large number of alveoli or 90 sockets 11 (see Fig. 3) sized, shaped and arranged as described and illustrated in the co-pending application above referred to.

As already stated, this improved construction is adapted for still further enhancing 95 the separating capacity of the grain separator without correspondingly increasing its volume inasmuch as both the outer and inner faces of the ring members 7 are formed with contiguous separating alveoli 11 and thus efficiently partake of the grain separation. The commingled grains are fed by an inlet pipe 12 at one extremity of the outer drum-like casing 4 and fill the bottom part of 100 said casing, wherein they are conveyed towards its opposite extremity by the rotation of the annular separating elements. The proper grains (wheat grains for instance) are thus picked up by the outer alveoli on the upwardly moving side of the said elements and dropped off or ejected at 13 on the 105 opposite side whence they fall on an in-

clined board 14 and into one or more discharging hoppers 15. Moreover, as the commingled grains can penetrate through the 5 passages 32 into the inner spaces between the outwardly converging ring members 7, they can also be picked up by the alveoli 11 formed on the inner faces of such members whereby the separating effect is largely increased. Within such inner spaces are provided 10 gutters or scoops 33 the purpose of which is to receive the proper grains thus picked up by the inner alveoli at the moment when they drop off therefrom due to the rotation of the ring members 7 and to 15 discharge them at 34 (see Fig. 2) whence they can fall on the board 14 and into the hoppers 15.

The gutters or scoops 33 have the shape of sharp isosceles triangles (see Fig. 4) for 20 snugly occupying the whole of the inner space between the outwardly converging ring members 7. They are pivotally connected upon thin rods 35 suspended from a longitudinal channel bar 36 fixedly secured 25 to the outer casing 4 and extending into the said inner spaces through the said narrow spaces 32 between the outer edges of the ring members 7. In Fig. 5 is illustrated by way 30 of example a method of adjustably securing the rods 35 upon the channel bar 36 by means of a screw-threaded portion and of three nuts 38. When it is desired to remove the 35 gutters 33 from the inner spaces 7^a between the outwardly converging ring members 7, all that is necessary is to bring them in 40 alignment with their respective carrying rods 35 and to turn the latter to the extent of 90°. The gutters are then brought edge-wise with respect to the annular passages 32 45 the width of which is larger than their thickness whereby a movement of translation is sufficient to remove them.

As above described, the ring members are 45 preferably formed adjacent the cylinder 6 with slits 10. Within the latter are thrust obliquely disposed blades 16 which are adapted to push onward the mass of grains from one groove or fluting to the succeeding ones. As the mass of grain travels 50 towards the outlet extremity of the casing 4, it is being continually subjected to the action of the alveoli 11, and the grains to be separated from such mass are removed in increasing proportion, so that on delivery the 55 mass contains only refuse grains.

In accordance with the patent statutes, the 60 principles of construction and operation of the invention as well as a convenient embodiment of same have been described. It will however be understood that the said invention is not limited thereto and that numerous modifications might be introduced without departing from its scope and spirit as will now be emphasized in the appended 65 claims.

What I claim and desire to secure by Letters Patent is:—

1. A grain separator of the type set forth comprising in combination an outer stationary elongated casing having a grain inlet at 70 one extremity, sorted grains discharging hoppers on one side and non-sorted grains discharging means at its other extremity, a rotary supporting cylinder mounted upon a longitudinal driving shaft and a plurality of 75 contiguous annular outwardly tapering separating elements fixed externally upon said cylinder so as to have a saw-tooth outline and each formed by a pair of symmetrically arranged frusto-conical ring members slightly 80 spaced along their outer edges and formed both on their outer and inner faces with a large number of contiguous alveoli adapted for picking up and afterwards dropping off and thus separating out the proper 85 grains from a mass of commingled grains fed at the inlet extremity of the separator, filling the lower portion of the casing and thus contacting with the said ring members in proportion as they rotate. 90

2. A grain separator of the type set forth comprising in combination an outer casing and a rotary cylinder mounted lengthwise therein and carrying a plurality of contiguous annular outwardly tapering separating 95 elements fixed externally upon same and made up of frusto-conical ring members arranged in co-operating pairs, each of which is constituted by a number of segments having sorting alveoli on both faces slightly 100 spaced apart and formed adjacent said cylinder with slits, oblique blades being engaged into said slits for propelling the refuse grains towards their outlet situated at the extremity of said casing opposite to the 105 inlet.

3. A grain separator of the type set forth comprising in combination a driving shaft, a rotary supporting cylinder rigidly mounted thereon, an outer drum-like casing 110 through which said cylinder freely extends longitudinally, a plurality of annular outwardly tapering separating elements fixed externally in juxtaposed relation upon said cylinder and made up of peripherally slightly 115 spaced frusto-conical ring members having sorting alveoli on their outer and inner surfaces, collecting scoops pivotally mounted on the said casing through the medium of supporting rods for swinging motion and snugly accommodated in the inner spaces between 120 said ring members for receiving the grains that drop off from the inner alveoli and bringing them to the discharging means on one side of the casing. 125

4. A grain separator of the type set forth comprising in combination a driving shaft, a rotary supporting cylinder mounted thereon, a plurality of annular outwardly tapering separating elements fixed upon said cylinder 130

and respectively made up of slightly spaced ring members having sorting alveoli on both faces, collecting scoops accommodated within in the inner spaces between said ring members and an outer stationary cylindrical casing enclosing the cylinder and the separating elements mounted thereon, said casing having an inlet for the commingled grains at one extremity, refuse grain discharging means at the other extremity and discharging hoppers for the sorted grains on one side.

5. A grain separator of the type set forth comprising in combination a driving shaft, a rotary supporting cylinder fixedly secured

upon said shaft, a plurality of contiguous annular outwardly tapering separating elements mounted externally upon said cylinder so as to provide a saw-tooth outline and each formed by a pair of frusto-conical ring members spaced along their free outer edges and provided on both their outer and inner faces with sorting alveoli, and a stationary outer drum-like cylindrical casing of a size to clear the said separating elements and having an inlet for the commingled grains at one extremity and discharging hoppers for the sorted grains on one side of the casing.

In testimony whereof I affix my signature.

CHARLES JEAN BAPTISTE VIGUERIE.
